DANIEL W. SHIEK, OF INDIANAPOLIS, INDIANA, ASSIGNOR TO WALTER L. MILLIKEN.
OF BARNSTABLE, MASSACHUSETTS.

SIGNAL MECHANISM FOR ADDING-MACHINES.

1,139,813.

Specification of Letters Patent. Patented May 18, 1915.

Application filed July 20, 1908. Serial No. 444,462.

To all whom it may concern:

Be it known that I, DANIEL W. SHIEK, a citizen of the United States, residing at Indianapolis, in the county of Marion and 5 State of Indiana, have invented certain new and useful Improvements in Signal Mechanism for Adding-Machines, of which the following is a description.

My invention relates to signal mechanism 10 for any suitable form of adding or calculating machine, and particularly to that type of machine known as the Burroughs adding machine, illustrated in Letters Patent of the United States granted to Alvin 15 Macauley, No. 823,474, dated June 12, 1906, and in the various Letters Patents of the United States granted to William S. Burroughs, mentioned therein, but the device is applicable in its essential features to 20 other adding machines of a similar character or intended for a similar purpose. The Burroughs machine and others of similar character or type are employed for the purpose of printing or recording a list of 25 items or amounts, adding up or accumulating such list and printing or recording at any time the total of the added items. In machines of this character it is essential that at the beginning of operations the machine shall be clear, *i. e.*, the adding wheels shall have nothing added upon them and shall stand at zero, or initial position, so 30 that when the list of individual items is printed or recorded and added and the machine operated to print or record a total of such list, the proper amount of such total will be printed or recorded and not have included in it any amounts standing upon the wheels at the beginning of operation. In 35 the ordinary use of machines of this character the printing of what may be termed a grand total clears the machine or *i. e.*, it turns the adding machine wheels to zero or initial position, the machine shown being 40 adapted to print a sub-total at any time without clearing the machine. With my device if the total has been taken and the machine not cleared a signal is given at the 45 next stroke or operation of the operating handle *i. e.*, if a sub-total has been taken and the wheels not turned to zero or initial position, there being no signal given in the preferred construction if the machine has 50 been cleared.

55 To this end and with these objects in

view, my invention consists in the novel construction, arrangement or combination of parts herein shown and described and more particularly pointed out in the claims.

In the drawings wherein like reference 60 characters indicate like or corresponding parts, Figure 1 is a view in elevation of the left side of the machine within the casing, the whole being shown partly in section, Fig. 2 is an enlarged view in elevation of a 65 portion of the same showing my construction as applied thereto. Fig. 3 is a view in elevation of my device showing the position of the parts as a step in the operation of the machine. Fig. 4 is a view in elevation 70 of the same showing the parts in position to give a signal at the next operation of the machine, Fig. 5 is a view in elevation of the same showing the position of the parts before the next operation of the machine after 75 a grand total has been taken, and Fig. 6 is a cross sectional view of my device taken substantially on line 6—6 of Fig. 2.

For a more detailed description of the 80 construction and operation of the machine illustrated in Fig. 1 of the accompanying drawings than hereafter given, reference may be had to the prior Macauley patent above mentioned and to the earlier patents referred to therein.

In order that my device may be clear it 85 will be necessary to give a brief description of the totaling and clearing mechanism of the machine shown. The keyboard of the machine comprises a plurality of rows of 90 keys 221 (Fig. 1) extending from front to rear of the machine, the keys in each row being numbered to represent the nine digits and the respective rows representing different denominations in increasing order from 95 right to left. Within the machine upon the central rocking shaft 600, (Fig. 1), are 100 hung a plurality of levers B (one for each row of keys) whose downwardly and forwardly extending arms 611 carry at their 105 forward ends upwardly extending gear tooth racks 610, whose teeth are adapted to mesh with the pinions 916 of the adding wheels which are mounted upon shaft 955 in the lower forward part of the machine, 110 said shaft being itself mounted in a rocking frame C arranged on a shaft 900. The rearwardly extending arms 611 of the levers B carry at their rear ends type plates 618 which are adapted to be forced against 115

the platen roller 619 over which the strip or sheet of paper upon which the printing is done is passed.

Each lever B is held in normal position 5 as shown in Fig. 1 by a latch controlled by the corresponding row of keys in the keyboard of the machine and when any key in any row is depressed the latch of the corresponding lever is tripped and the front end 10 of the lever and the rack 610 carried by it are released so that they may (later) swing downward until arrested by a stop projected into the path of one of the moving parts by the operated key. The downward movement 15 of the front end of the lever B will be accompanied by an upward movement of its rear end, which carries the type plates 618, and the adjustment of parts is such that the movement permitted the lever prior to its 20 being arrested by the stop of the operated key will bring a particular type representing the value of such key into printing position immediately in front of the platen 619. The levers B do not move immediately 25 upon the tripping of their latches by the operated keys but only upon subsequent movement of the operating handle (not shown). The operating handle is connected with the rock shaft 600 by a train of mechanism 30 not necessary to be here illustrated or described whereby when the operating handle is pulled forward the shaft 600 will be rocked in the same direction. The levers B are reset or restored to normal position 35 by the levers 613 which are connected by a cross bar 617, the levers being controlled or operated by the operating handle of the machine in a manner not necessary to give in detail here. If the racks 610 of the levers 40 B remained in mesh with the pinions 916 of the adding wheels during the downward movement of the racks, at the forward movement of the operating handle the pinions and adding wheels would be turned distances 45 corresponding to the values of the operated keys. In the machine shown however, the pinions 916 are swung forward and out of mesh with the racks 610 at the forward movement of the operating handle and downward movement of the released racks, 50 so that they are not turned by the racks during the downward movement of the latter; but at the return upward movement of the parts the pinions are swung rearwardly into 55 mesh with the racks and turned by the latter distances corresponding to the previous downward movement of the racks. This is accomplished by mounting the supporting shaft 955 of the pinions 916 in a swinging 60 frame composed of two side arms C located at opposite sides of the machine and fast upon the opposite sides of the rock shaft 900. The upper end of one of these arms C is bifurcated as shown in Figs. 1 and 2 and 65 co-operates with the stop 205 which limits

the forward and backing movement of the rocking frame carrying the pinions. This rocking frame is operated for the purpose mentioned in the following manner and by the following means: Pivotaly supported 70 upon a stud 941 projecting inward from the left hand side frame of the machine is a three-armed lever 913 whose vertically depending arm has pivoted to its lower end the rear end of a forward extending arm 75 914 which is supported near its forward end by a long link 911, depending from a stud upon the front end of a bell crank 227 fulcrumed upon the framework of the machine at 204 and having at its forward end 80 an upwardly extending stem 227^a, carrying a finger piece 265. This bell crank 227 and its stem 227^a and finger button 265 constitute the total key of the machine which is yieldingly held in and returned to normal 85 position (Fig. 1) by springs acting upon other parts of the machine connected with it and not necessary to be referred to here. It suffices for present purposes to say that the upper end of the link 911 is supported 90 by the key or bell crank 227 and that the lower end of the link is pivoted to and supports the forward end of the arm 914. At its front end this arm 914 is divided into two diverging arms 914^a and 914^b the former 95 of which extends upward immediately adjacent the side arms C of the rocking frame carrying the pinions and is provided with a notch engaging a stud 958 on said side arm. Under this arrangement of parts it will be 100 understood that if the arm 914 be swung bodily forward by forward movement of the lower end of the vertical arms of the lever 913 and the lower end of the link 911 it will force forward the rocking frame carrying the pinions and disengage them from the racks 610. This movement of the parts is accomplished at the forward movement of the operating handle by the following 105 means: Journaled in the lower part of the machine is a rock shaft 800, suitably connected with the operating handle in such a manner that the forward movement of the handle rocks the shaft 800 backward in the direction of the arrow in Fig. 1. Fast upon the shaft 800 is a three-armed lever 813, whose upwardly and forwardly extending arm 813^a carries a pivoted wiper block or plate 821, adapted to co-operate with studs 961 and 961^a upon the backwardly and forwardly extending arms of the three-armed lever 913. A spring 833 connected by a rod or wire to the lower end of the pivoted plate 821, tends to swing said plate into alignment with the lever arm 813, upon which the plate is pivoted and in the position of the parts shown in Fig. 1, holds the upper end of said plate against the rear side of the stud 961^a. When the operating handle is 115 pulled forward, and the shaft 800 thereby 120 125 130 135 140 145 150 155 160 165 170 175 180 185 190 195 200 205 210 215 220 225 230 235 240 245 250 255 260 265 270 rocked in the direction of the arrow, the upward and rearward movement of the lever arm 813^a will engage one of the shoulders of the pivoted plate 821 with the stud 961^a of the three-armed lever 913, thereby forcing upward the forward arm of said lever and swinging forward its depending vertical arm which latter will force forward the arm 914 and cause its upwardly and forwardly extending front arm 914^a; engaging the stud 958 to swing forward the rocking frame C carrying the pinions 916, and disengage the latter from the rack 610, so that the racks may swing downward with out turning the pinions.

The operations thus described, due to the forward movement of the operating-handle, will have swung the lever-arm 813^a and its pivoted plate 821 rearward into proximity with the stud 961 on the rearwardly-projecting arm of the lever 913, and at the end of the forward movement of the operating-handle the pivoted plate 821 will stand in substantially the same relation to the stud 961 that it occupies in respect to the stud 961^a in Fig. 2, its upper end bearing against the forward side of the stud and the plate itself being rocked upon the lever-arm 813^a to a position opposite that occupied by it in Fig. 2. At the return or backward movement of the operating-handle the rock-shaft 800 will be rocked forward to normal position and as the lever-arm 813^a swings forward the rear shoulder upon the pivoted plate 821 will engage the stud 961 of the lever 913 and force the rearwardly-projecting arm of said lever upward, thereby swinging its vertically-depending arm rearward and drawing the arm 914 backward to normal position, and in this backward movement the arm C will carry the rocking frame with it, owing to the engagement of the notched end of the arm 914^a with the stud 958 upon the frame C thereby reengaging the pinions 916 with the racks 610 at the beginning of the return movement of the operating-handle, so that as the levers 611, carrying the racks, are returned to normal position by the restoring-frame 613 and 617 the pinions and adding-wheels will be turned distances corresponding to the previous downward movements of the respective racks.

It will be understood that at the end of the forward movement of the operating-handle and of the downward movements of the respective racks which have been released by the operations of the keys in the rows corresponding to them the type-plates 618, carried by the rear ends of the levers B will have been swung upward into positions to present at the printing-line immediately in front of the platen 619 the respective types corresponding to the values of the operated keys, and while the parts are in such posi-

tion at the end of the forward movement of the operating-handle those types are forced rearward against the platen by means of strikers or hammers, in a manner not necessary to describe in detail, to effect the printing of the amount represented by the operated keys, an inked ribbon being passed between the types and the paper upon the platen-roll.

Under the operation above described merely the amount of the individual item represented by the operated keys will be printed upon the strip or sheet of paper, and it will be next in order to explain how the total of all of the amounts or items accumulated upon the adding-wheels may at any time be printed. It will be understood that if the pinions of the adding-wheels were allowed to remain in mesh in the racks 610 during the downward movement of the latter the pinions would be turned backward by the downward movement of the racks. The pinions are free to turn backward upon their shaft 955 to but not beyond zero position. If, therefore, any rack be allowed to swing downward while in mesh with its pinion, it will turn such pinion backward until the pinion reaches zero position whereupon the arresting of the pinion will arrest the movement of the rack. Thus if the pinion and its adding-wheel be standing at "9" it can turn backward nine-tenths of a revolution and the rack engaged with it can move downward a corresponding distance. If it be standing at "5", it can move backward five-tenths of a revolution and the rack a corresponding distance, and so on, with the result that if all of the racks be released and the operating-handle be drawn forward while the pinions are permitted to remain in mesh with the racks each pinion will be turned backward the exact distance which it has been previously moved forward from zero position, and the racks will all be permitted to move downward corresponding distances, and this downward movement of the racks will cause corresponding upward movements of the type-plates 618, carried by the rear ends of the levers B, so that there will be brought to the printing-line the types corresponding to the numbers which have been displayed upon the adding-wheels. In other words, the totals which have been displayed upon the adding-wheels will by the return of these wheels to zero position be transferred to and presented by the types at the printing-line at the rear end of the machine, so that by then forcing said types rearward against the platen the total of all the items previously added upon the adding-wheels may be printed upon the strip or sheet of paper. The pinions are left in mesh with the racks whenever it is thus desired to print a total by throwing out of operative posi-

tion the arm 914, whose forward movement disengages the pinions from the racks in the manner heretofore explained. This is accomplished by depressing the total-key 265, 5 which through the medium of the link 911 swings the front end of arm 914 downward and disengages its member 914^a from the stud 958 upon the pinion-carrying frame C, so that when the operating-handle is then 10 pulled forward the arm 914 will move idly forward and leave the frame C in its normal position, with the pinions 916 in engagement with the racks 610.

If the pinions were permitted to remain 15 in mesh with the racks during the return upward movement of the latter, at the release and backward movement of the operating handle they would be turned forward again to the respective positions which they 20 occupied prior to the operation of printing the total in the manner described, so that at the end of the operation there would remain accumulated upon the adding-wheels the amount which had previously been added 25 upon them, and succeeding items or amounts would thereafter be added to this aggregate of the proceeding items. This is permitted when it is desired to merely print what is termed a "subtotal" and not clear 30 the machine; but for the purpose of printing what may be termed a "grand" total and clearing the machine means are provided for swinging the pinions of the adding-wheels out of engagement with the racks 35 prior to the return upward movement of the latter, so that the pinions and adding-wheels will be left in zero position at the end of the operation of the machine and the latter be thereby cleared. This is accomplished 40 by means of the hooked lower end of the depending member 914^b of the arm 914, which hooked end is adapted to coöperate with a stud 958^a upon the lower end of the side arm C of the pinion-carrying frame. 45 The depression of the total-key 265 swings this hooked end of the arm 914 downward into proximity to the stud 958^a and when the arm 914 is moved forward at the forward movement of the operating handle the 50 hook catches over the stud 958^a and when the arm 914 is then drawn rearward again at the beginning of the rearward movement of the operating-handle, as heretofore explained the engagement of the hook with 55 the stud pulls the lower end of the rocking frame C rearward and swings its upper end forward and disengages the pinions from the racks, so that the latter may move upward to normal position without turning 60 the pinions. In printing a subtotal and not clearing the machine the total-key 265 is depressed and held down while the operating handle is drawn forward, but is released and permitted to swing upward (and to draw 65 the front end of the arm 914 upward with

it) prior to the backward movement of the handle, with the result that the hooked arm 914^b will not engage the stud 958^a upon the rocking-frame C at the backward movement of the handle and the pinions will be left 70 in mesh with the racks during the return upward movement of the latter and be thereby turned forward again to the positions which they occupied prior to the downward movement of the racks. 75

As will be understood from the foregoing description, the operation of printing a total and clearing the machine consists in depressing the total-key 265 and holding it down during both the forward and backward movements of the operating-handle, while the operation of printing a subtotal and not clearing the machine consists in depressing the total-key and pulling forward the operating-handle and then releasing the 85 key prior to the backward movement of the handle. The depression of the total-key serves by means not necessary to be described in detail to trip the latches of all of the racks, so that the latter will be free 90 to move downward at the forward movement of the operating-handle to the extent permitted by the respective pinions with which they are engaged.

It is unnecessary to explain the means employed for forcing the type against the platen roller 619 to effect the printing other than to say that at each operation of the machine at the end of the forward movement of the operating handle the type plates are 95 forced against the platen roller 619 as described in the Macauley patent mentioned and the patents referred to therein. It is also unnecessary to enter into any other details of the Macauley and the other machines as to the features which have nothing to do with my invention. 100

Referring now to the drawings in which my preferred form of device is shown and which as before stated is designed to give a 105 signal at the succeeding operation of the machine after a total has been taken and at which time the machine was not cleared, levers or arms 1 and 2 are loosely arranged on the shaft 900. The arm 1 is provided with a resilient member 13 or its equivalent 110 tending to normally force the upper end of the arm against a stop 14, the lever being normally held in the position shown in Figs. 1 and 2 by means of a bell crank arm 5—6 115 pivotally arranged on the arm C and co-operating with the lug or extension 9 on the extended portion 914^a of the arm 914. As shown, the bell crank arm 6 is provided with a pin 4 or its equivalent which engages or 120 contacts with the face 8 of the bifurcated end of the arm 1, a resilient member 10 or its equivalent tending to normally keep the pin 125 in contact with the face 8 when the arm 5 is not in engagement with the lug 9, on the 130

arm 914. The arm 2 is provided with a substantially cam-faced extension 11 adapted to coöperate with a pin or lug 12 or its equivalent on the forked end 914^b of the 5 arm 914, a resilient member 3 or its equivalent tending to normally hold the arm 2 against the stop 14. Pivotaly supported within the machine, preferably on shaft 942, is arranged another substantially bell-crank 10 lever or arm 15—16, provided with a resilient member 17 or its equivalent tending to normally draw the arm into a position as shown in Fig. 4. As shown the arm 16 is provided with an extension or lug 18 adapt- 15 ed to coöperate with the arms 1 and 2 as will be more fully explained hereinafter. A ratchet 19 or its equivalent for the purpose is also preferably loosely arranged on the shaft 942 and is engaged by a pawl 21 piv- 20 otally secured to the arm 16 and normally resiliently held in mesh with the ratchet wheel 19 by a resilient member 22 or its equivalent. Pivotaly secured at 23 or other convenient place is an arm 24 adapted to co- 25 operate with the ratchet 19 a resilient member 33 tending to normally retain the two in engagement. As shown, the arm 24 is ex- 30 tended as at 25 and provided with a hammer or striker 26 secured thereto adapted to strike the bell 27 or its equivalent to give the signal when the device operates as is more fully explained in the description of the operation of the machine. An arm 28 is also preferably pivotally secured to the 35 arm 813 at 29, the same being normally held substantially in a position relative to the arm 813 as shown in Fig. 1 by means of a resilient member 31 or its equivalent and the stop 30.

40 The operation of my device is substantially as follows: Assuming first that a total is printed, the key 265 being held down during the forward and backward movements of the operating handle so that the 45 machine is cleared as heretofore described, in which case in the preferred construction shown no signal is to be given on the next operation of the operating handle. As before stated depressing the total key 265 50 swings the front end of arm 914^a from the stud 958 on the frame C, so that when the operating handle is pulled forward the pinions 916 will remain in mesh with the racks 610, the pinions being disengaged from the racks 55 upon the rearward movement of the operating handle. As the key 265 is depressed the pin 12 on the arm 914 contacts with the extension 11 on the arm 2 and forces the same out of engagement with the lug 18 on the arm 16, the resilient member 13 at the 60 same time drawing the arm 1 in the path of the lug 18 on the arm 16 and retaining the same in substantially the same position. This movement of the arm 1 is permitted 65 owing to the lug 9 on the arm 914 substan-

tially releasing the arm 5 of the bell crank 5—6. It should be noted that the lower end of the arm 1 is shorter than the corresponding end of the arm 2 so that when arm 1 is in engagement or contact with the lug 18 70 on the arm 16 the arm 2 cannot engage the lug without moving the arm 16. The arm 1 is then in the position substantially as shown in Fig. 3 retaining the bell crank arm 15—16 in the position shown in this figure. 75 As the operating handle is thrown over, the arm 914 is drawn into proximity to the stud 958^a and when the arm 914 is drawn rearward again at the beginning of the rearward movement of the operating handle, as 80 heretofore explained, drawing the lower end of the rocking frame C, the pinions are thrown out of mesh with the racks. Owing to this rearward movement of the arm 914, the lug 9 misses the arm 5 of the bell-crank 85 5—6 so that the arm 1 controlled thereby does not release the arm 16 but retains the same substantially in position as shown in Fig. 3. At the operation of the operating handle forward, as described, the arm 813 90 moves in a direction indicated by the arrow so that the member 28 contacts with the pin 32, but the bell-crank 15—16 which is retained in position by the arm 1 substantially as shown in Fig. 3, is not moved 95 sufficiently to rotate ratchet 19 before the member 28 passes beyond the pin 32. As the operating handle is moved back, the arm 16 is retained in the position shown by the arm 1; the resilient member 31 permitting the 100 arm 28 to pass the pin 32. The totaling key 265 is now released, so that arm 2 takes the position substantially as shown in Fig. 3. On the next operation of the operating handle the arm 813 is again rotated and 105 the arm 28 again engages the pin 32 on the arm 15, raising the same again slightly and the arm 2 having been released by the pin or lug 12, is drawn by the resilient member 3 back to the normal positions shown in 110 Figs. 1 and 2, there being no signal given, thus indicating that the machine was cleared on the preceding operation. It may be here noted that at this time the arm 5 and lug 9 after this operation are in positions substantially as shown in Fig. 5. Mention will be made of this hereafter. 115

Assuming now that the machine was not cleared, that is, the adding wheels were not returned to zero but contained what may be called the sub-total, the parts being substantially as shown in Figs. 1 and 2. If the totaling key 265 is depressed and the operating handle thrown forward, the totaling key being released before the backward movement of the operating handle, there will be a total on the adding wheels. As in the previous case when the totaling key 265 is pressed down, the arm 2 is thrown out of engagement with the lug 18 on the arm 16 and 120

the arm 1 thrown into contact therewith as shown in Fig. 3. The operating handle is then thrown forward but before its return movement key 365 is released. This causes 5 rod 911 to draw up the end of the arm 914, the lug 9 engaging the arm 5 of the bell crank 5-6 (the arm 914 being forward) so that the arm 16 is released, the arm 6 having drawn the arm 1 into the position as shown 10 in Fig. 4. Releasing arm 16 permits the resilient member 15 to draw the bell crank 15-16 substantially into the position shown in Fig. 4. This moves the pawl 29 back several teeth on the ratchet 19 so that on the 15 next operation of the operating handle, the arm 28 engages the pin 34 of the arm 15, thus rotating the ratchet 19 and thereby vibrating arm 34 and striker 26, thus ringing the bell 27 and indicating that the 20 machine was not cleared at the time the preceding total was printed. As the arm 28 raises the arm 15, pivoting ratchet 19, the arm 16 is thereby caused back to a position as shown in Figs. 1 and 2 before the arm 28 disengages 25 with the pawl 29 thus permitting the arm 1 to be thrown forward so that the parts are again at normal operative position. It is also seen that when the bell crank 5-6 is again engaged by the lug 19 of the arm 30 28 it will be disengaged and returned to a position as shown in Figs. 1 and 2. In the case of disengaging and disengaging when the arm 5 was 35 engaged by the lug 9 on the return stroke, as shown in Fig. 5, it is obvious that it will be disengaged and returned to a position as shown in Figs. 1 and 4 at the next time that a signal is taken. While I have shown a mechanism comprising a bell 40 adapted to give an audible signal, it is obvious that any other suitable signal may be given to indicate the condition of the machine.

Having thus described my invention, it is obvious that various immaterial modifications may be made in the construction, arrangement or combination shown and described and that the device may be applicable on other machines than the type mentioned, without departing from the spirit of my invention; hence, I do not wish to be understood as limiting myself to the exact construction, arrangement and combination of parts shown and described.

What I claim as new and desire to secure by Letters Patent is:

1. In a device of the kind described, an adding machine comprising mechanism arranged to accumulate and totalize individual items and sum the total thereof either with clearing the adding mechanism or retaining 5 the total thereof, and controlling means for the total printing mechanism in combination with means operative on the retention of a total for rendering a signal at the next succeeding operation of the printing mechanism 10 and means for connecting a plurality of arms 1 and

2 operatively associated with the totalizing mechanism, a bell crank lever 15-16 controlled thereby, and means for transmitting the movement of lever 15-16 to a bell.

2. In a device of the kind described, an adding machine comprising mechanism arranged to accumulate and totalize individual items and print the total thereof either with clearing the adding mechanism or retaining the total thereon, and controlling means for the total printing mechanism, in combination with signal mechanism normally operative on the retention of a total for rendering a signal at the next succeeding operation of the printing mechanism, comprising a plurality of arms 1 and 2, a bell crank lever 15-16 controlled thereby, and means operatively associated with the totalizing mechanism for actuating said bell crank lever.

3. In a device of the kind described, an adding machine comprising mechanism arranged to accumulate and totalize individual items and print the total thereof either with clearing the adding mechanism or retaining the total thereon, and controlling means for the total printing mechanism, in combination with signal mechanism normally operative on the retention of a total for rendering a signal at the next succeeding operation of the printing mechanism, comprising a plurality of arms 1 and 2, a bell crank lever 15-16 controlled thereby, actuating mechanism for said lever operatively associated with the totalizing mechanism co-operating with the operating mechanism of the machine, and means for operatively transmitting the movement of the lever to a bell.

4. In a device of the kind described, an adding machine comprising mechanism arranged to accumulate and totalize individual items and record the total thereof either with clearing the adding mechanism or retaining the total thereon, and controlling means for the total recording mechanism, in combination with means operative on the retention of a total for rendering a signal at a succeeding operation of the printing mechanism comprising a plurality of arms 1 and 2 operatively connected with the totalizing mechanism, an arm controlled thereby, means for transmitting the movement of said arm to give a signal, and means for resetting said signal mechanism to operative position substantially simultaneously with the operation thereof.

5. In an adding machine comprising printing and adding mechanism arranged to accumulate and totalize individual items, and means for recording the total and retaining said total on the register after it has been recorded, in combination with a bell, an elongated arm pivoted intermediate its ends having a hammer at one end, and means actuated by the totalizing mechanism 120

key for engaging the free end of said arm to move the hammer into engagement with the bell whenever a total has been retained by a previous printing operation.

5 6. In an adding machine comprising printing and adding mechanism arranged to accumulate and totalize individual items, and means for recording the total and retaining total on the register after it has been recorded, in combination with a bell, an elongated arm pivoted intermediate its ends having a hammer at one end, and a rotatable device actuated by the totalizing mechanism for engaging the free end of said arm to move the hammer into engagement with the bell whenever a total has been retained by a previous printing operation.

7 7. In an adding machine comprising printing and adding mechanism arranged to accumulate and totalize individual items, and means for recording the total and retaining said total on the register after it has been recorded, in combination with a bell, an elongated arm pivoted intermediate its ends having a hammer at one end, and a rotatable device having an irregular surface to engage the free end of said arm, and means operatively associated with and actuated by the totalizing mechanism for actuating said rotatable device to move the hammer in contact with the bell whenever a total has been retained by a previous operation.

8 8. In an adding machine comprising printing and adding mechanism arranged to accumulate and totalize individual items, and means for recording the total and retaining said total on the register after it has been recorded, in combination with a bell, an elongated arm pivoted intermediate its ends, having a hammer at one end, said arm being operable at its free end, a ratchet member, and a said dog to move the hammer into engagement with the bell, when a total has been retained by a previous printing operation, and means associated with and actuated by the totalizing mechanism for operating the ratchet.

9 9. An adding machine arranged to accumulate and totalize individual items, and means for recording the total and retaining said total on the register after it has been recorded, in combination with a bell, a movable hammer, and means operatively connected with said totalizing mechanism for imparting a series of vibrations to the hammer whenever a total has been retained by a previous printing operation.

10 10. An adding machine arranged to accumulate and totalize individual items, and means for recording the total and retaining said total on the register after it has been recorded, in combination with a signal, and key and means for operating the signal including an elongated arm pivoted

intermediate its ends having means at one end to engage the signal, and a rotatable device to engage the opposite end of said arm, said rotatable device being operatively connected with the totalizing mechanism.

70

11. In a device of the kind described, an adding machine comprising mechanism arranged to accumulate and totalize individual items and print the total thereof either with clearing the adding mechanism or retaining the total thereon, and controlling means for the total printing mechanism, in combination with means operative on the retention of a total for rendering a signal at the next succeeding operation of the printing mechanism, comprising a plurality of arms 1 and 2, a bell crank lever 15-16 controlled thereby, a bell, a bell hammer, and means operatively connected with totalizing mechanism and the bell crank lever for actuating said hammer.

75

80

85

12. In a device of the kind described, an adding machine comprising mechanism arranged to accumulate and totalize individual items and print the total thereof either with clearing the adding mechanism or retaining the total thereon, and controlling means for the total printing mechanism, in combination with means operative on the retention of a total for rendering a signal at the next succeeding operation of the printing mechanism, comprising a plurality of arms 1 and 2, a bell crank lever 15-16 controlled thereby, a bell, a bell hammer, and means operatively connected with totalizing mechanism and the bell crank lever for actuating said hammer.

90

95

100

13. In a device of the kind described, comprising mechanism arranged to accumulate and totalize individual items and print the total thereof either with clearing the adding mechanism or retaining the total thereon, and controlling means for the total printing mechanism including a total key, in combination with signal mechanism normally inoperative upon the clearing of the machine, for indicating the retention of a total at a preceding operation of the printing mechanism, comprising a bell crank lever 15-16, means for imparting movement thereto through said total key, a signal, and means between the lever 15-16 and signal for actuating the latter.

105

110

115

120

125

130

14. In a device of the kind described, comprising mechanism arranged to accumulate and totalize individual items and print the total thereof either with clearing the adding mechanism or retaining the total thereon, and controlling means for the total printing mechanism including a total key, in combination with signal mechanism normally inoperative upon the clearing of the machine, for indicating the retention of a signal.

135

140

145

total at a preceding operation, of the printing mechanism, comprising a bell crank lever, movable parts actuated by the key for imparting movement to the lever, a ratchet actuated by the lever, and dog actuated means co-operating with the ratchet to sound a signal.

15. In a device of the kind described, a casing, mechanism arranged to accumulate and totalize individual items, and print the total thereof, either with clearing the adding mechanism or retaining the total thereon, and controlling means for the total printing mechanism including a total key, in combination with a stationary member adapted to emit a sound, a movable member adapted to be moved into contact with said member, means for normally holding said parts separated, and means for bringing 20 said parts into contact on the retention of a total at the next succeeding operation of the printing mechanism.

16. In a device of the kind described, the combination of accumulating and totalizing mechanism having associated means for clearing the device, means to engage the sounding device to cause a signal, to indicate whether or not a total has been retained in a previous operation of the adding mechanism, and means for operatively connecting the last mentioned means with the totaliz-

ing mechanism whereby the signal is actuated by the latter, and means actuated by the clearing means to release said operative connection between the sounding device and 35 totalizing mechanism upon the operation of the clearing means.

17. A device of the kind described having in combination mechanism to accumulate and totalize individual items, clearing mechanism, an operating lever adapted in one movement to actuate the totalizing mechanism and in a subsequent movement to actuate the clearing mechanism, a sounding device, and operating means therefor operatively connected with the clearing and totalizing mechanism, whereby in the first mentioned movement of said lever the sounding device is actuated to indicate that the machine is not clear, and whereby the second mentioned movement of said lever to clear the machine will prevent the last mentioned action of the sounding device in a succeeding operation of the lever.

In testimony whereof, I have hereunto signed my name in the presence of two subscribing witnesses.

DANIEL W. SHIEK.
